ONE-PIECE CONTAINER

Howard D. Randall, Cincinnati, Ohio, assignor to
The Randall Company, Cincinnati, Ohio, a cor-
poration of Ohio

Application June 11, 1934, Serial No. 730,009

3 Claims. (Cl. 229—51)

This invention relates to a one-piece container such as may be used for packaging a group of sheets, for example sheets of copy paper or the like for use upon typewriters and similar machines.

An object of the invention is to provide a one-piece container of the above stated character, which may conveniently and easily be opened in such a manner as to provide for easy removal of the sheets contained therein while at the same time preserving the sheet-protective function or character of the container.

A further object of the invention is to reduce the cost of packaging various kinds of sheets which are sold or delivered as relatively small groups, and which, in many cases, the sheets are removed periodically until the container is empty.

The foregoing and other objects are attained by the means described herein and disclosed in the accompanying drawing, in which:

Fig. 1 is a top plan view of the device of the invention.

Fig. 2 is an enlarged cross-sectional view taken on line 2—2 of Fig. 1.

Fig. 3 is a longitudinal cross-sectional view, on an enlarged scale, taken on line 3—3 of Fig. 1.

Fig. 4 is a view showing the one-piece blank of which the Fig. 1 device is formed.

The container of the present invention is constituted of a blank having a plane top member 5 with an integral front end flap 6 and an integral rear end flap 7, these being scored as at S to provide, respectively, the front and rear walls 8 and 9 of the container. The blank also has a pair of integral opposed bottom wall members 10 and 12, the width of each of which may conveniently be made approximately half the width of the top member 5. The bottom wall members may be scored as at T to form the side walls 13 and 14 of the container. Upon bending downwardly, along the various score lines, the end and side flaps just referred to, a completely closed container will be formed, and the formation may be maintained by applying a connecting means or strip 15 to the bottom wall members so as to join them in accordance with the disclosure of Fig. 2. The connecting means 15 may be adhesively or otherwise secured to the bottom wall members 10 and 12 exteriorly of the container.

From the foregoing it will readily be understood that the blanking and formation of the container results from a simple and easily performed rapid machine operation.

The forward end of the container is peculiarly treated, by means of a punching and cutting oper-

ation, to render the sheets in the container easily accessible by complete removal of the front end wall, its associated flap 6, and part of the top member 5, which elements form the end closure means of the container. The treatment referred to comprises striking or cutting through the material of the top member 5, at a distance from the adjacent score lines S, to provide a pull tab 16 in the plane of the top wall member and extending in a direction rearwardly of said top wall member, the length of the tab being determined by the dead ends 17 of the cut which forms the tab. Said dead ends 17 are spaced considerably from the adjacent scores S, for a reason to be explained later. From the points 18 and 19, which are the corners of the front end of the top member 5, the material of the top is intermittently punched or otherwise weakened along lines 20 and 21, which lines converge toward the rear of the container and which, if extended, would meet at a point, such as P, upon the tab 16. The convergent lines, however, end approximately at the dead ends 17 of the tab cut upon the top member 5.

With the construction above described, the user upon desiring to open the container and gaining access to the contents thereof, merely grasps the tab 16 and pulls it forwardly sufficiently to tear the material of the top member along the weakened portions 20 and 21, whereupon the entire end closure constituted of the removable top section 22, tab 16, end wall 8, and flap 6, become disassociated completely from the container. The removal of the top section 22 provides a convenient upper recess in the top member 5 whereby the user's fingers will have easy access to the forward ends of the sheets within the container. The opening thus provided at the front end of the container will be ample and unobstructed for free removal of sheets therefrom, and the opened container will not be unsightly or marred in appearance at the opened end thereof.

As will readily be evident, the wall members 8, 9, 13 and 14 may be so reduced in width or height as to become practically negligible, in which case the thickness of the container will be reduced to a minimum, but the front end closure will still perform as above set forth.

It is to be understood that various modifications and changes in the structural details of the device may be made, within the scope of the appended claims, without departing from the spirit of the invention.

What is claimed is:

1. A container of the class described comprising a top wall member, a bottom, a pair of side walls, a front wall, and a rear wall, and a front end closure means for the container comprising the front wall and a flap which are constituted of an extension of the forward end of the top wall member, the line of juncture of the front wall and the top wall member forming opposed forward corners of the container, a tab struck from the material of the top wall member at a distance from said line of juncture and providing a cut with dead ends terminating at a distance from said line of juncture but forwardly of the center of the tab, each of the dead ends of the cut being connected with the aforesaid opposed forward corners of the container by a material-weakening cut, whereby a forward manual pulling of the tab results in complete removal of the tab, the front wall, the flap connected to said front wall, and that portion of the top wall member which is forwardly of the material-weakening cuts, so as to provide an unobstructed access opening at both the top and the adjacent front ends of the container, said material-weakening cuts being inwardly convergent toward the rear of the container but falling short of actual meeting at the dead ends of the tab cut.
2. As a new article of manufacture, a one-piece container blank comprising a top wall member having front, rear, and side limits determined by score lines arranged in rectangular formation, front, rear, and side wall members extending outwardly from the corresponding limits of said large top member, and flaps extending outwardly of each of said front, rear, and side wall members, the flaps which extend from the side wall members being of such width as to provide a bottom for the container when folded inwardly and toward the top wall member, and a front end closure means including the front wall member and its associated flap, a tab struck from the material of the top wall member at a distance from the score line which determines the front flap and providing a cut with dead ends terminating at a lesser distance from the last mentioned score line, each of the dead ends of the cut being connected with the forward corners of the rectangular top wall member by a material-weakening cut, whereby a forward manual pulling of the tab results in complete removal of the tab, the front wall, the flap, and that portion of the top wall member which is forwardly of the material-weakening cuts, as and for the purposes described.
3. As a new article of manufacture, a one-piece container blank comprising a top wall member having front, rear, and side limits determined by score lines applied to the material of the blank in a substantially rectangular formation, front, rear, and side walls extending outwardly from the corresponding score lines which determine the limits of the top wall member as stated above, flaps extending outwardly of each of said walls, the flaps which extend from the side walls of the container blank being of such width as to provide a bottom for the container when folded inwardly and toward the top wall member, and a front end closure means including the front wall, the front flap, and a tab struck from the material of the top wall member at a distance from the score line which determines the front wall, said tab being formed by a cut with dead ends terminating at a lesser distance from the last mentioned score line, each of the dead ends of the cut being connected, by a material-weakening cut, with the score lines which distinguish the side walls from the side edges of the top wall member, whereby a forward manual pulling of the tab results in complete removal of the tab, the front wall, the front flap, and that portion of the top wall member which is forwardly of the material-weakening cuts, as and for the purposes described.

HOWARD D. RANDALL.
